UNITED STATES PATENT OFFICE

JOSEPH OSIP, OF NORTHAMPTON, AND JOHN KOLEMBA, OF MOUNT TOM,
MASSACHUSETTS

BREECH LOADING ORDNANCE

Application filed September 13, 1932. Serial No. 632,976.

This invention relates to certain new and useful improvements in breech loading ordnance.

The primary object of the invention is to provide a breech loading ordnance or artillery cannon of the type mounted upon a wheeled carriage and capable of being transported by means of a truck, tractor or other hauling apparatus and including devices to accomplish range adjustments by shifting the barrel of the cannon laterally of the carriage as well as on a horizontal pivot.

A further object of the invention is to provide a breech loading ordnance of the foregoing character wherein a cartridge or shell conveyor is adjustably mounted on the wheeled carriage for vertical and lateral adjustment movements relative to the breech mechanism of the cannon for delivering a cartridge or shell to a position for feeding into the breech chamber.

A still further object of the invention is to provide an improved breech mechanism for an artillery cannon embodying a novel construction of interlocking devices for retaining the breech block or bolt within the breech chamber of the cannon.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a top plan view of a breech loading ordnance constructed in accordance with the present invention, showing the cannon adjustably supported upon a wheeled carriage;

Figure 2 is a side elevational view showing the vertical adjusting devices associated with the conveyor that delivers shells to the breech of the cannon;

Figure 3 is a vertical longitudinal sectional view taken on line 3—3 of Figure 1, showing the devices to accomplish vertical adjustment of the cannon barrel and lateral adjustment thereof together with the brake for the carriage wheels.

Figure 4 is a vertical cross-sectional view taken on line 4—4 of Figure 2;

Figure 5 is a fragmentary side elevational view of the cannon body or barrel with the firing pin of the breech mechanism illustrated in its retracted cocked position and further illustrated by dotted lines in its fired position;

Figure 6 is a fragmentary side elevational view of the barrel of the cannon showing the latch cover for the open side of the breech chamber moved to open position with the breech bolt rotated to a position to permit removal thereof from the breech chamber;

Figure 7 is a fragmentary side elevational view, similar to Figure 6, with the breech bolt partially removed by means of a rack and pinion device;

Figure 8 is a fragmentary longitudinal sectional view of the breech end of the cannon barrel showing the tensioned firing pin;

Figure 9 is a cross-sectional view, similar to Figure 4 and illustrating the adjustment devices for the shell conveyor;

Figure 10 is a detail sectional view of the laterally shiftable block for the vertical adjusting screw at the forward end of the shell conveyor; and

Figure 11 is a detail sectional view showing the sliding block for the elevation adjusting screw of the shell conveyor mounted in a channel guide.

Referring more in detail to the accompanying drawings, the breech loading ordnance comprises a wheeled carriage including an elongated frame plate 15 provided at one end with a ground engaging foot 16, carrying depending side aprons 17 with a cross-axle 18 journaled through the forward ends of the side aprons 17 by means of bearings 19 shown in Figure 3, the cross axle 18 extending laterally of the frame plate 15 and carrying ground wheels 20. The ground engaging foot 16 carries a clevis engaging link 21 to facilitate attachment to the wheel carriage of a truck, tractor or other means of transporting the wheeled frame.

As shown more clearly in Figures 1 to 4 and 9, side bearings 22 rise from the forward end of the frame plate 15 of the wheeled carriage for the support of a pair of spaced guide

shafts 23. A frame for the support of a cannon body is slidably mounted upon the guide shafts 23 and is of U-shape as shown in Figs. 3, 4 and 9 and includes a bottom wall 24 having perpendicular side walls 25 rising therefrom, the front and rear edges of the bottom wall 24 being of rack bar formation as at 26. A longitudinal shaft 27 extends through the cannon support between the side walls 25 thereof, being mounted at its rear end in a bearing 28 rising from the frame plate 15 of the wheeled carriage while the forward end of the shaft 27 is journaled in a guard wall 29 suitably secured to the forward side of the bearings 22. A pinion 30 is carried by each end of the shaft 27 and has meshing engagement with the adjacent rack bar 26, each end of the shaft 27 being provided with a crank handle 31 to facilitate rotation thereof for the transverse adjustment of the cannon support as will at once be obvious from an inspection of Figures 3, 4 and 9.

A cross shaft 32 is journaled transversely of the upper ends of the side walls 25 of the cannon support and upon which shaft a pair of plate members 33 are pivotally supported intermediate their ends, the plate members 33 being perpendicularly disposed with inwardly directed angle flanges 34 at their upper ends to be respectively received in longitudinally extending side grooves 35 formed in the cannon barrel 36. A rack segment 37 is fixed as at 38 to the inner face of each plate member 33, centering on the shaft 32, depending therefrom and extending below the plate members 33 for supporting and meshing engagement with pinions 39 and 40 fixed to shafts 41 and 42 respectively, the two shafts 41 and 42 being journaled in the side walls 25 of the U-shaped cannon support with the shaft 42 extending outwardly of the side walls 25 and carrying upon each projecting end thereof a ratchet wheel 43 engaged by a pawl 44, one terminal end of the shaft 42 carrying a hand crank 45 to facilitate rotation thereof. It will be understood that when the shaft 42 is rotated by means of the crank handle 45, pivotal movement is imparted to the plate members 33 carrying the cannon barrel 36 for raising or lowering the muzzle end of the barrel, the pawl and ratchet devices maintaining angular adjustments of the barrel 36.

The slidable mounting of the cannon barrel 36 upon the plate members 33 permits recoil movement of the barrel, the plate members 33 carrying a top connecting wall 46 disposed beneath the barrel 36 with a lug 47 extending from the wall 46 and having one end of a recoil spring 48 attached thereto with the other end of the spring 48 being connected to a lug 49 depending from the cannon barrel 36, as illustrated in Figure 3, the spring 48 normally urging the cannon barrel in a forward direction. The forward

guard wall 29 is provided with an opening 50 through which the cannon barrel 36 extends.

The breech mechanism of the cannon is shown more clearly in Figures 5 to 8 and includes a breech chamber 51 in which a tubular breech bolt 52 is mounted. The tubular breech bolt carries a firing pin 53 tensioned as at 54, the rear end of the breech bolt extending rearwardly of the breech chamber 51 as at 52a. Cocking means for the firing pin 53 includes a pull device 55 fixed to the rear projecting end of the firing pin 53 and working in the slot 56 at the underside of the breech bolt extension 52a, the pull device 55 being retracted by means of the handle 57 to retract the firing pin 53 against the tension of the spring 54 and upon rotation of the pull device 55 together with the firing pin 53, the pull device is moved laterally of the breech extension slot 56 to be engaged with the rear terminal end of the extension 52a to maintain the firing pin in a retracted cocked position.

A side wall of the breech chamber 51 is cut away as at 58 to accommodate the mounting of the sliding breech bolt and the side opening is closed by a hinged gate 59 carrying a pivoted latch 60 engageable with a keeper 61 on the inner end of the cannon barrel 36.

Means is provided for placing the breech bolt in the breech chamber 51 and includes rack and pinion mechanism, the strap 62 depending from the breech bolt extension 52a supporting one end of a rack bar 63 that extends into a channel guide 64 carried by the lower side of the gun barrel beneath the breech chamber. A manually operated pinion 65 is journaled in lugs 66 depending from the channel guide 64 and is in meshing engagement with the rack bar 63 so that upon operation of the pinion 65, the breech bolt may be moved into and out of the breech chamber.

The breech bolt and cannon barrel are cooperatively constructed to form an interlocking connection between the breech bolt and barrel when the breech bolt is entirely received within the breech chamber, the breech bolt 52 being surrounded by a sleeve 67 rotatable thereon and carrying a laterally projecting loop strap 68 passing through the side opening 58 in the breech chamber and projecting laterally of the cannon barrel. When the breech bolt has been completely positioned within the breech chamber 51, the side legs of the loop strap 68 register with the side notches 69 formed in a side wall of the breech chamber at one edge of the opening 58, as shown in Figure 6 so that upon partial rotation of the sleeve 67 upon the breech bolt by pressing downwardly upon the loop strap 68, the spaced side legs thereof move into the notches 69 to lock the breech bolt in the breech chamber. The gate 59 is then closed upon its hinge mounting

59a and the latch 60 engaged with the keeper 61. A shell extractor 70 is carried by the forward end of the breech bolt and has an angle end 71 extending into a circumferential slot 72 in the sleeve 67 permitting rotation of the sleeve independently of the shell extractor.

Conveyor means is provided for delivering a shell to the breech chamber and as shown in Figures 1, 2 and 9 to 11, an inclined track 73 is slidably mounted at its lower end upon the shaft 74 extending transversely of the lower end of the frame plate 15 and mounted in brackets 75 while the upper end 15 of the inclined conveyor track 73 carries a block bearing 76 threaded upon the substantially perpendicular screw shaft 77 having an operating handle 78 upon its upper end and swivelled at its lower end as at 79 in a bearing 80 and slidably interlocked with angle flanges 81 extending transversely of the frame plate 15 beneath the breech end of the cannon. A pulley 82 is journalled at the upper and lower ends of the inclined 20 conveyor track 73 and the two pulleys are traversed by an endless cable 83, the run of which overlies the track carrying a feeder or follower 84 for moving shells 85 as shown in Figure 1 over the trackway to the head 30 thereof and in a position to be delivered into the breech chamber 51 of the cannon. The endless feed cable 83 is operated by a crank handle 86 associated with the pulley 82 at the head of the track 73.

35 The upper end of the conveyor track 73 carries a lateral chute 87 directed toward the breech chamber and is caused to register with the breech chamber by operation of the screw shaft 77. After a shell 85 has been delivered to the head of the track, the slide member 88 is manually operated to move the shell over the chute 87 and deliver the same to the breech chamber. As shown in Figure 40 9, a tensioned pin 89 extends through a wall of the breech chamber and carries upon its inner end a shoe 90 that is engaged by the nose of the shell, the tensioned pin 89 being manually operated to elevate the shoe 45 and nose of the shell into alignment with the bore of the cannon barrel so that when the breech bolt is mounted in the breech chamber, the shell is automatically delivered into the shell receiving portion of the barrel.

50 It is to be understood that the tensioned pin 89 and shoe 90 may be omitted and the device will be otherwise operable for the passage of the shell into the shell receiving portion of the barrel.

55 The forward guard wall 29 above the plate 15 is of double wall construction providing guides for slidable guard plates 91 that are manually shiftable by means of finger grips 2 to close around cannon barrel and carrying frame while steps 93 carried by the guard

wall 29 facilitate access to operating devices for parts of the mechanism.

Brake mechanism for the wheels 20 includes a cross-arm 94 as shown in Figs. 1 to 3 disposed beneath the frame plate 15 and passing through guides 95 carried by the depending aprons 17 with a brake shoe 96 on each end of the cross bar. The cross bar is further supported by means of rods 97 having eye-ends 98 freely rotatable on the cross 75 axle 18. A brake rod 99 is attached at one end thereof as at 100 to the bar 94 intermediate its ends, the forward end of the brake rod 99 extending through the guard wall 29 and being threaded for the reception of a 80 brake wheel 101.

From the above detailed description of the invention, it is believed that the construction and operation thereof will at once be apparent, and while there is herein shown and described the preferred embodiment of the invention, it is nevertheless to be understood, that minor changes may be made therein without departing from the spirit and scope 85 of the invention as claimed.

Having thus described the invention, what is claimed is:—

1. In a breech loading cannon, a wheeled carriage, a support shiftable transversely of the carriage, a cannon and carrying frame with the latter horizontally pivotally mounted on the support, a frame plate on the wheeled carriage, the transversely shiftable support being of substantially U-shape with a bottom wall and perpendicular side walls 100 and guide shafts on the carriage for the support.

2. In a breech loading cannon, a wheeled carriage, a support shiftable transversely of the carriage, a cannon and carrying frame with the latter horizontally pivotally mounted on the support, recoil devices interposed between the cannon and carrying frame, a frame plate on the wheeled carriage, the transversely shiftable support being of substantially U-shape with a bottom wall and perpendicular side walls and guide shafts on the carriage for the support.

3. In a breech loading cannon, a wheeled carriage, a support shiftable transversely of the carriage, a cannon and carrying frame with the latter horizontally pivotally mounted on the support, a frame plate on the wheeled carriage, the transversely shiftable support being of substantially U-shape with a bottom wall and perpendicular side walls and guide shafts on the carriage for the support, rack bars extending between the side edges of the spaced walls of the support, a manually rotatable shaft traversing the rack bars and pinions on the shaft engaged with the rack bars for shifting the support.

4. In a breech loading cannon, a wheeled carriage, a support shiftable transversely of the carriage, a cannon and carrying frame

- with the latter horizontally pivotally mounted on the support, recoil devices interposed between the cannon and carrying frame, a frame plate on the wheeled carriage, the 5 transversely shiftable support being of substantially U-shape with a bottom wall and perpendicular side walls and guide shafts on the carriage for the support, rack bars extending between the side edges of the spaced 10 walls of the support, a manually rotatable shaft traversing the rack bars and pinions on the shaft engaged with the rack bars for shifting the support.
5. In a breech loading cannon, a wheeled carriage, a support shiftable transversely of the carriage, a cannon and carrying frame with the latter horizontally pivotally mounted on the support, a frame plate on the wheeled carriage, the transversely shiftable support 15 being of substantially U-shape with a bottom wall and perpendicular side walls and guide shafts on the carriage for the support, the cannon carrying frame including side plate members pivotally mounted on the side walls 20 of the support, a rack segment fixed to each plate member and centering on the plate pivots, pinions supported on the walls in meshing engagement with the rack segments and manually operable means for one set of 25 pinions for pivoting the cannon and carrying frame on the support.
6. In a breech loading cannon, a wheeled carriage, a support shiftable transversely of the carriage, a cannon and carrying frame 30 with the latter horizontally pivotally mounted on the support, a recoil device interposed between the cannon and carrying frame, a frame plate on the wheeled carriage, the transversely shiftable support being of substantially U-shape with a bottom wall and perpendicular side walls and guide shafts on the carriage for the support, the cannon carrying frame including side plate members pivotally mounted on the side walls of the support, a rack segment fixed to each plate member and centering on the plate pivots, pinions supported on the walls in meshing engagement with the rack segments and manually operable means for one set of 35 pinions for pivoting the cannon and carrying frame on the support.
7. In a breech loading cannon, a wheeled carriage, a support shiftable transversely of the carriage, a cannon and carrying frame 40 with the latter horizontally pivotally mounted on the support, a frame plate on the wheeled carriage, the transversely shiftable support being of substantially U-shape with a bottom wall and perpendicular side walls and guide shafts on the carriage for the support, the cannon carrying frame including side plate members pivotally mounted on the side walls of the support, a rack segment fixed to each plate member and centering on the plate pivots, pinions supported on the walls in meshing engagement with the rack segments and manually operable means for one set of 45 pinions for pivoting the cannon and carrying frame on the support.
5. In a breech loading cannon, a wheeled carriage, a support shiftable transversely of the carriage, a cannon and carrying frame 50 with the latter horizontally pivotally mounted on the support, a frame plate on the wheeled carriage, the transversely shiftable support being of substantially U-shape with a bottom wall and perpendicular side walls and guide shafts on the carriage for the support, the cannon carrying frame including side plate members pivotally mounted on the side walls of the support, a rack segment fixed to each plate member and centering on the plate pivots, pinions supported on the walls in meshing engagement with the rack segments and manually operable means for one set of 55 pinions for pivoting the cannon and carrying frame on the support.
7. In a breech loading cannon, a wheeled carriage, a support shiftable transversely of the carriage, a cannon and carrying frame 60 with the latter horizontally pivotally mounted on the support, a frame plate on the wheeled carriage, the transversely shiftable support being of substantially U-shape with a bottom wall and perpendicular side walls and guide shafts on the carriage for the support, the cannon carrying frame including side plate members pivotally mounted on the side walls of the support, a rack segment fixed to each plate member and centering on the plate pivots, pinions supported on the walls in meshing engagement with the rack segments and manually operable means for one set of 65 pinions for pivoting the cannon and carrying frame on the support.

non carrying frame including side plate members pivotally mounted on the side walls of the support, a rack segment fixed to each plate member and centering on the plate pivots, pinions supported on the walls in meshing engagement with the rack segments and manually operable means for one set of pinions for pivoting the cannon and carrying frame on the support.

8. In a breech loading cannon, a wheeled carriage, a support shiftable transversely of the carriage, a cannon and carrying frame with the latter horizontally pivotally mounted on the support, recoil devices interposed between the cannon and carrying frame, a frame plate on the wheeled carriage, the transversely shiftable support being of substantially U-shape with a bottom wall and perpendicular side walls and guide shafts on the carriage for the support, rack bars extending between the side edges of the spaced walls of the support, a manually rotatable shaft traversing the rack bars and pinions on the shaft engaged with the rack bars for shifting the support, the cannon carrying frame including side plate members pivotally mounted on the side walls of the support, a rack segment fixed to each plate member and centering on the plate pivots, pinions supported on the walls in meshing engagement with the rack segments and manually operable means for one set of pinions for pivoting the cannon and carrying frame on the support.

9. In a breech loading cannon, a wheeled carriage, a support shiftable transversely of the carriage, a cannon and carrying frame with the latter horizontally pivotally mounted on the support, a frame plate on the wheeled carriage, the transversely shiftable support being of substantially U-shape with a bottom wall and perpendicular side walls and guide shafts on the carriage for the support, rack bars extending between the side edges of the spaced walls of the support, a manually rotatable shaft traversing the rack bars and pinions on the shaft engaged with the rack bars for shifting the support, the cannon carrying frame including side plate members pivotally mounted on the side walls of the support, a rack segment fixed to each plate member and centering on the plate pivots, pinions supported on the walls in meshing engagement with the rack segments and manually operable means for one set of pinions for pivoting the cannon and carrying frame on the support, and pawl and ratchet devices associated with the rack segment and pinion mechanism for holding the cannon and carrying frame in pivotally adjusted position.

10. In a breech loading cannon, a wheeled carriage, a support shiftable transversely of the carriage, a cannon and carrying frame with the latter horizontally pivotally mounted

- on the support, recoil devices interposed between the cannon and carrying frame, a frame plate on the wheeled carriage, the transversely shiftable support being of substantially U-
5 shape with a bottom wall and perpendicular side walls and guide shafts on the carriage for the support, rack bars extending between the side edges of the spaced walls of the support, a manually rotatable shaft traversing
10 the rack bars and pinions on the shaft engaged with the rack bars for shifting the support, the cannon carrying frame including side plate members pivotally mounted on the side walls of the support, a rack segment
15 fixed to each plate member and centering on the plate pivots, pinions supported on the walls in meshing engagement with the rack segments and manually operable means for one set of pinions for pivoting the cannon
20 and carrying frame on the support, and pawl and ratchet devices associated with the rack segment and pinion mechanism for holding the cannon and carrying frame in pivotally adjusted position.
25 11. In a breech loading cannon, a wheeled carriage, a cannon carried thereby, a conveyor track adjustable on the carriage for the delivery of shells to the cannon breech, the conveyor track having its upper end disposed
30 adjacent the breech of the cannon, a vertical screw adjustment for the upper end of the track and transverse adjustments for the lower end of the screw and the lower end of the track.
35 12. In a breech loading cannon, a wheeled carriage, a cannon carried thereby, and breech mechanism including a breech bolt and an end opening breech chamber in the cannon; a rack bar on the breech bolt and a manually
40 operable pinion on the cannon engageable with the rack bar for moving the breech bolt into and out of the breech chamber with the
rack bar located exteriorly of the breech chamber.
13. In a breech loading cannon, a wheeled carriage, a cannon carried thereby, breech mechanism including a breech bolt and an end opening breech chamber in the cannon, a rack bar on the breech bolt and a manually operable pinion on the cannon engageable with the rack bar for moving the breech bolt into and out of the breech chamber, a sleeve
70 rotatable on the breech bolt and cooperating means carried by the sleeve and cannon for retaining the breech bolt in the breech chamber.
14. In a breech loading cannon, a wheeled carriage, a cannon carried thereby, recoil devices interposed between the cannon and carrying frame, breech mechanism including a breech bolt and an end opening breech chamber in the cannon, a rack bar on the breech bolt and a manually operable pinion on the cannon engageable with the rack bar for moving the breech bolt into and out of the breech chamber with the rack bar located exteriorly of the breech chamber, a sleeve rotatable on the breech bolt and cooperating means carried by the sleeve and cannon for retaining the breech bolt in the breech chamber.
80
15. In a breech loading cannon, a wheeled carriage, a cannon shiftably carried thereby, a guard wall at the forward end of the carriage having an opening through which the cannon extends and guard plates slidible into contacting relations with the cannon for closing the opening when the cannon is shifted into different positions.
90
In testimony whereof we affix our signatures.
